Des. 2318

Samuel H. Hanson of Allentown, Pa.

Letters Patent No. 2318, Dated May 15, 1886.

Design for the Plate of a Cook's Store.

The schedule referred to in this letter is to be made part of the same.

Shall where it may concern:

With his usual intent to secure the same by letters patent, and to have the same registered, I do hereby declare and request a design for the front of a cook's store, and to declare that the following is a full and exact description of the same, reference being made to the accompanying photographs:

A represents the design for front door;

B " " " front;

C " " " side;

D " " " rear door;

Together forming plates for cook's store "Kewada".

This is new and distinct accessory by letters Patent.

The design for plates of cook's store as shown and described.

Witness,

Geo. D. Miller
J. A. H.

J. H. Hanson
